PROCESS OF MOUNTING CREMATORIY NICHE FRAMES

Filed Oct. 14, 1931

FIG. 1.

FIG. 2.

INVENTOR.
Lawrence F. Moore
BY
Harry C. Schroeder
ATTORNEY

UNITED STATES PATENT OFFICE

LAWRENCE F. MOORE, OF PIEDMONT, CALIFORNIA

PROCESS OF MOUNTING CREMATORIAL NICHE FRAMES

Application filed October 14, 1931. Serial No. 568,832.

The invention is for a method of mounting crematory niche frames.

The object of the invention is to provide a neat and convenient method of mounting and attaching niche frames in a crematory, whereby said frames may be plumbed and located after the cooperating mounting parts are installed.

Another object of the invention is to provide means for mounting and installing a niche frame whereby cooperating mounting parts may readily be installed at any time after construction of the niche, no great degree of accuracy being required in locating the cooperating mounting elements, the niche frame being plumbed and located after installation of the cooperating elements.

In the accompanying drawings:

Fig. 1 indicates a niche frame installed and mounted according to my method;

Fig. 2 indicates the cooperating mounting elements in position about a niche, ready to receive the niche frame;

Fig. 3 is an enlarged sectional view showing the frame and cooperating element for one point of attachment and using a standard type of screw used for mounting niche frames;

Fig. 4 is a similar view to Fig. 3 except indicating the frame attached by means of a progressive screw adapted to drill and tap the mounting plate in advance of the screw portion.

Similar reference characters are used to designate similar parts throughout the several views in which a niche is indicated by numeral 1 and the surrounding walls by numeral 2. A niche frame 3 is shown mounted in position by means of rosette headed screws 4. A packing strip or gasket 5 is disposed between the frame 3 and wall 2 and a glass 6 inserted in the frame and retained from the rear of the frame by means of small clips and screws.

The parts so far enumerated are not a part of the invention.

The invention consists of the method of mounting the frame 3 onto the front surface of walls 2, and comprises a number of apertures 7, corresponding to the number of

screws 4 used for attaching the frame, formed in the front face of the niche walls. Plugs 8, preferably of lead or lead alloy, provided with small diameter holes 9 axially disposed are inserted in the apertures 7. 55 Plates 10 are provided with a countersunk hole 11 for reception of the head of an ordinary flat head wood screw 12. With the plugs 8 tightly fitted in apertures 7, plates 10 are located with hole 11 registering with hole 9 in plugs 8. An ordinary wood screw 12 screwed into hole 9, expands the plug 8 and tightly retains the plug 8 and plate 10 in relative position.

Following installation of the required number of mounting plates 10, as indicated in Fig. 2, the niche frame 3 is placed in position and the holes for reception of screws 4 transferred to the plates. The plates 10 are then drilled and tapped, and the frame attached by means of screws 4. Or, by means of the progressive screw 13, which is the subject of a separate application for patent under preparation, the frame may be positioned, and by means of a special chucking brace adapted to receive the head of the screw, the screw is inserted in one of the holes of the frame and the hole drilled and tapped in the plate, the screw being driven tight, thereby doing away with two individual operations.

Having described an operative and desirable method of mounting niche frames, what I claim is:

1. The method of mounting a frame consisting of forming apertures in the front face walls about an opening, inserting plugs therein adapted to receive wood screws, attaching plates to the plugs by means of the wood screws, and tapping the plates in registry with the mounting holes in a niche frame after positioning the niche frame over the opening.

2. The method of mounting and attaching a niche frame, consisting of inserting plugs, adapted to receive ordinary countersunk head wood screws, in the front face of the walls about a niche and in relative position to the mounting holes in the frame, attaching plates to the walls by means of the screws

cooperating with the plugs, positioning the frame over the niche, transferring the holes from the frame to the plates, drilling and tapping the plates in position, and attaching the frame by means of the frame mounting screws.

5. The method of mounting niche frames consisting in anchoring lead or lead alloy plugs having small apertures therein for starting a wood screw below the surface of the front face of the walls about a niche, and positioning relative to the mounting holes in the niche frame, attaching plates to the plugs by means of wood screws, and
10. drilling and tapping in the plates after attachment to the plugs, the holes being located from the mounting holes in the niche frame after positioning the niche frame relative to the niche.
15. 4. The method of mounting niche frames consisting in attaching plates by means of screws to plugs anchored in a wall and positioned relative to the mounting holes in a niche frame, locating holes in the plates by
20. means of the frame or a template of the frame in desired position, the holes being drilled and tapped to receive the niche frame mounting screws.
25. 5. The method of mounting niche frames
30. consisting of attaching plates by means of screws to plugs secured in a wall and positioned relative to the mounting holes in a niche frame, positioning the frame relative to a niche and attaching the frame by means of
35. a progressive screw adapted to drill and tap said holes in advance of the screw portion.
6. The method of mounting and attaching niche frames consisting in anchoring plugs in a wall and attaching plates thereto in relative position to the mounting holes in the niche frame, and drilling and tapping holes registerable with the niche frame mounting holes, and adapted to receive the niche frame mounting screws, after attachment of the
40. plates to the plugs.
45. 7. The method of mounting and attaching niche frames consisting in forming holes in the wall about the niche, anchoring soft metal plugs adapted to receive a tapered
50. screw in the holes, attaching plates to the plugs by means of the tapered screws, whereby the plug is expanded in the hole by the taper of the screw, and drilling and tapping holes after attachment of the plates
55. to the plugs, the holes being positioned so as to be registerable with the mounting holes in the niche frame, and adapted to receive the niche frame mounting screws.

60. In testimony whereof I have affixed my signature.

LAWRENCE F. MOORE.
